MEANS FOR AND METHOD OF SUPPORTING
THE ROOFS OR WALLS OF UNDERGROUND
WORKINGS

Otho S. Batten, Pikeville, Ky.

Application January 28, 1944, Serial No. 520,088

9 Claims. (Cl. 61—45)

This invention relates to means for and methods of supporting the roofs or walls of underground workings and more particularly to means for supporting such a roof or wall while leaving the adjacent working area free from encumbrances so as to provide ample working space for the workmen and machinery, and to a novel method of supporting the walls of underground workings.

The majority of serious accidents that occur to men actively engaged in mining or tunneling occur at the active working faces. Heretofore it generally has been the practice to use timber or steel beams in connection with vertical posts to support the overlying strata or roof of a mine to prevent its falling on the men actively engaged at the face. With the advent of mechanical loading, and especially in thin seams of coal, the timbering at the working face has interfered materially with the efficiency of the loading equipment. For this reason, the timbering often has been neglected with the result that serious injuries and a number of fatalities have occurred.

In accordance with my invention a steel band or the like, varying in width and thickness to meet the requirements, is held against a roof or wall so as to support it safely and surely without encumbering the working area.

An object of the invention is to provide a new and improved means for supporting a wall, e. g., the roof, of an underground working.

Another object is to provide means of the character stated which is light, of simple construction, and which is adapted to support substantial loads without interfering with men and machinery in the working area.

Another object of the invention is to provide supporting means of the kind referred to in which a thin supporting band is first held taut closely against the wall to be supported, but is permitted to sag slightly when loaded, the sagging of the band increasing its load supporting capacity.

A further object of the invention is to provide a new and improved method of supporting a wall, e. g., the roof, of an underground working.

Other objects will become apparent from a reading of the following detailed description, the appended claims, and the accompanying drawings, in which:

Figure 1 is a horizontal section through an underground working approximately at the roof level and showing roof supporting means in top plan;

Figure 2 is a vertical section on the line 2—2 of Figure 1;

Figure 3 is a side elevation of one end portion of a supporting band structure, drawn on an enlarged scale;

Figure 4 is a top plan view of the structure shown in Figure 3;

Figure 5 is a section on the line 5—5 of Figure 4;

Figure 6 is a plan view of a shear plate;

Figure 7 is a section on the line 7—7 of Figure 4;

Figure 8 is a fragmentary detail view in vertical section showing the relative positions occupied by a prop and supporting band structure before the structure is loaded fully; and

Figure 9 is a view similar to Figure 8 but showing the related positions of the parts after the structure is loaded.

By way of example, the invention is disclosed as being practised in the working of a coal mine cut shown in Figures 1 and 2 as comprising a floor A, roof B, and side walls C and D. The undercutting proceeds in the direction of the arrow E, the back of the undercut being indicated by the line F. The portion of the working indicated by the brace a has been cleared of coal, and the portion indicated by the brace b contains the cut of coal to be loaded out.

In accordance with the invention, the roof over the area being cleared is supported by novel means which leave the area unencumbered so that there is ample room for movement of the workmen and operation of loading and trans-

porting machinery. After removal of the cut coal, struts or posts which may be of a more or less permanent and conventional nature, are placed under the roof of the area. Supporting means embodying the invention are then placed

under the roof of the next in-by area so as to assure that this area will remain safe for working and will be unobstructed so as to provide all space necessary for the men and machinery. The cutting and loading out then proceeds further in the direction of the arrow E, and as each new area is cut and cleared the roof supporting means of the invention are moved in.

With this general mode of operation in mind, the construction and the method of using a preferred embodiment of the invention will be readily understood. Figure 2 shows elongated supporting devices generally designated 1 spaced from each other in the direction of the arrow E, extending transversely of the mine working, and terminating just short of the walls C and D. The

elongated supporting devices 1 may all be of the same construction. Each device 1 comprises a thin flexible elongated band-like member 2 preferably formed of alloy steel. At or adjacent each end of each member 2 is a reinforcing plate 3 welded to the associated member 2 as at 4 or secured in any other suitable way. Elongated openings 5 extend through the members 2 and reinforcing plates 3 with their longer dimensions extending longitudinally of the member 2.

In use, the members 2 are placed closely underneath the roof B and are drawn taut and placed under longitudinal tension by holding connections between the mine working and the devices 1. For this purpose prop elements 6-6 are interposed between the floor A and the longitudinally spaced end portions of the member 2, the prop elements being inclined outwardly and upwardly from the floor A to the roof B. The elements 6 are extensible for simultaneously pressing the end portions of the member 2 against the roof and for stressing the member longitudinally. Preferably the prop elements 6 comprise jacks which may be operated either manually or by any suitable power applying means, e. g., electrically, pneumatically, or hydraulically. In the form shown ordinary manually operated screw jacks are provided.

Before placing the jacks 6, the roof B and floor A preferably are formed with cut-outs 7-7 and 8-8, respectively, for receiving the top and bottom portions of the jacks. The upper portions 9 of the jacks extend through the openings 5 previously referred to.

The upper end portions 9 of the jacks may fit snugly between the sides of the elongated openings 5 but there is clearance 12 to allow considerable relative longitudinal movement between the jacks and the member 2. In accordance with one feature of the invention yieldable means are provided for holding the end portions 9 of the jacks against the inner ends of the openings 5 as shown in Figure 8. For this purpose a shear plate 13 is mounted to extend across the clearance space 12 between the jack upper end portion 9 and the outer end of the associated opening 5. Preferably, the shear plates 13 are mounted on the member 2 so as to be readily replaceable. In the embodiment shown each shear plate is formed with inclined ends which converge inwardly toward the adjacent outer end of the member 2 and toward the longitudinal axis thereof. Angle pieces 14, welded to the band-like member 2 as at 15, are disposed at inclinations corresponding to the inclinations of the ends of the shear plate 13, the arrangement being such that the shear plate end portions can be slipped under the overhanging flanges of the angle pieces 14 as shown in Figures 4, 5 and 7.

Assuming that coal has been cut but not yet removed from the area a, the roof will be unsupported and the struts 16 and caps 17 will not yet be in place. A plurality, for example three, of the devices 1 are placed successively in closely underlying relation to the roof B as shown in Figures 1 and 2 with the thin or smallest dimensions of the band-like members 2 being normal to the roof. The jacks 6 are positioned as shown in Figure 2 with abutment plates 10 contacting the reinforcing plates 3 and with abutment plates 11 contacting the floor A. The projecting end portions of the jacks will extend into the cut-outs 7 and 8 previously formed in the roof B and floor A. The shear plates 13 are mounted as shown in Figures 4, 5, 7, and 8 so as to extend across the

clearances 12, thereby holding the jack upper portions 9 at the inner ends of the openings 5. The jacks 6 are then operated to press upwardly against the reinforcing plates 3 and the band members 2 will be stretched longitudinally and placed under tension.

The roof B over the devices 1 may fail and move downwardly so as to impose an additional load on the devices 1. This will stress the bands 2 more greatly, tending to pull the ends of the bands inwardly. The yieldable shear plates 13 will then give way, permitting the band ends to move inwardly a limited distance equal to the clearances 12 after which the outer end parts of the openings 5 will engage the upper portions 9 of the jacks, as shown in Figure 9, preventing further inward movement of the band ends. In this way the bands 2 will be permitted to sag and their load-carrying capacities will be increased. In Figure 1, the right hand end of one of the devices 1 is shown at x as having moved inwardly to sag-producing position consequent upon failure of the associated shear plate (not shown).

It will be apparent that, in order to provide for the sagging of the bands so as to increase their load-carrying capacities, the elongated openings 5 may be formed at either or both ends of the bands. In the illustrative embodiment, the band ends are shown as being of identical construction but if desired the devices could be constructed to provide for the relative movement of the bands and jacks at one end only of each band. It also will be apparent that the shear plates 13 constitute only one of several means which may be provided for initially holding the band substantially straight and taut but being adapted to give way to permit limited movement of one or both ends of the band so as to bring about sagging.

As shown in Figure 1, three supporting devices 1 are positioned under the roof B of the area a for supporting the roof while the cut coal is being loaded out. After an area has been cleared it usually is desirable to support the roof B more or less permanently by means of conventional struts or posts 16 provided with caps 17. These may be set in place while the devices 1 are still in supporting position.

When a new cut has been made in the area b and before removing the coal, supporting devices of the kind previously described are positioned as indicated in dotted lines at 18. The roof B will then be supported over the area b while leaving ample room for the workmen and machinery to operate in removing the coal. This procedure is repeated for each new cut as the working or tunneling is carried forward in the direction of the arrow E. If desired, the supporting devices 1 may be removed from each area after the struts 16 and caps 17 have been set in place, the removed supporting devices then being used for supporting the newly undercut roof.

The novel supporting means embodying my invention is very light and easy to handle. A quarter-inch thick steel band twenty-four feet long will support a greater load than an 8 inch by 10 inch timber cross header of substantially equal length. By using supporting devices embodying the invention the workmen are afforded ample room for moving about and for operating loading machinery but are always protected from the newly undercut roof. If the roof should break it would be supported by the sagging bands 2 until the permanent shoring struts 16 could be set in place.

The supporting devices 1 have been disclosed as comprising steel alloy band-like members 2 formed as flat strips or sheets, but it will be apparent that any strong and fairly flexible members, such as ropes or woven wire bands properly reinforced at their ends, could also be used. As used in this specification and the claims the term "band-like member" is intended to mean flat strips or sheets as shown in the illustrative embodiment, or assemblies of multiple cables, ropes, narrow strips or any elongated flexible members equipped at their ends to be held in place as explained above.

The most common use of supporting devices embodying the invention is for supporting the roof of a mine or other underground working. However, devices embodying the invention may also be used for supporting or preventing the caving in of working walls other than roofs, in which cases the jacks 6 are extended between the supporting devices 1 and a wall opposed to that which is being supported.

Although the construction shown herein by way of example embodies the invention in its preferred form, it will be understood that changes may be made without departing from the invention as defined in the claims.

I claim:

1. In means for supporting the roof of an underground working, a thin flexible member closely underlying the roof; and holding connections between the working and opposite end portions of said member for holding said member in place under said roof and for resisting movement of said member end portions towards the center of said member, one of said holding connections comprising a part adapted to give way when said member is loaded to thereby release the associated end portion of said member for limited movement toward the other of said end portions and to thus permit said member to sag.

2. In means for supporting the roof of an underground working, a thin flexible member closely underlying the roof; and holding connections between the working and opposite end portions of said member for holding said member in place under said roof and for resisting movement of said member end portions towards the center of said member, one of said holding connections comprising a prop interposed between the floor of said working and said member, a part on said member engageable with said prop and adapted to give way when said member is loaded to thereby release the associated end portion of said member for limited movement toward the other of said end portions to thus permit said member to sag, and another part on said member engageable with said prop after such movement of the prop-held end portion for preventing further movement thereof.

3. In means for supporting the roof of an underground working, a thin flexible member closely underlying the roof; and holding connections between the working and opposite end portions of said member for holding said member in place under said roof and for resisting movement of said member end portions towards the center of said member, one of said holding connections comprising an opening in the associated end portion of said member, an element anchored in said working and extending through said opening with clearance longitudinally of said member outwardly beyond said element, and a yieldable part carried by said member and overlapping said clearance and engaging said element to hold said

member under tension, said yieldable part being adapted to yield when said member is subjected to a predetermined load and is placed under increased tension, whereby said member end portion is permitted to move toward the member central portion to an extent equal to said clearance and said member is permitted to sag.

4. In means for supporting the roof of an underground working, a thin flexible band-like member closely underlying the roof with its thin or smallest dimension normal to the roof; props interposed between end portions of said member and the floor of the working and being inclined from bottom to top outwardly towards the ends of said member respectively; an opening in one end portion of said member through which the associated prop extends with clearance longitudinally of said member outwardly beyond said props; and a shear plate secured to said member and extending across said clearance and engaging said prop.

5. In means for supporting the roof of an underground working, a thin flexible band-like member closely underlying the roof with its thin or smallest dimension normal to the roof; props interposed between end portions of said member and the floor of the working and being inclined from bottom to top outwardly towards the ends of said member respectively; an opening in one end portion of said member through which the associated prop extends with clearance longitudinally of said member outwardly beyond said prop; a shear plate; and means detachably mounting said plate on said member to extend across said clearance in engagement with said prop.

6. In means for supporting the roof of an underground working, a thin flexible band-like member closely underlying the roof with its thin or smallest dimension normal to the roof; props interposed between end portions of said member and the floor of the working and being inclined from bottom to top outwardly towards the ends of said member respectively; an opening in one end portion of said member through which the associated prop extends with clearance longitudinally of said member outwardly beyond said prop; a shear plate adapted to extend transversely of said member and across said clearance and having ends converging towards the longitudinal center and adjacent end of said member; and a pair of angle pieces connected to said member at inclinations respectively conforming to the plate end inclinations and being adapted to hold said plate to extend as aforesaid.

7. In means for supporting a wall of an underground working, a thin flexible member lying closely against said wall; and holding connections between the working and opposite end portions of said member for holding said member in place against said wall and for resisting movement of said member end portions towards the center of said member, one of said holding connections comprising a part adapted to give way when said member is loaded to thereby release the associated end portion of said member for limited movement toward the other of said end portions and to thus permit said member to sag.

8. In means for supporting a wall of an underground working, a thin flexible band-like member lying closely against said wall; props interposed between end portions of said member and the wall of said working opposed to said wall to be supported and being inclined from said opposed wall outwardly towards the ends of said

member respectively; an opening in one end portion of said member through which the associated prop extends with clearance longitudinally of said member outwardly beyond said prop; and a shear plate secured to said member and extending across said clearance and engaging said prop.

9. In a method of supporting the roof of an

underground working, applying a thin flexible elongated member closely underneath said roof; anchoring one end of said member to said roof; and yieldably anchoring the other end of said member to said roof for limited movement of said other end towards said one end.

OTHO S. BATTEN.
